UNITED STATES PATENT OFFICE.

BYRON B. CARTER, OF CHICAGO, ILLINOIS, ASSIGNOR TO THE M. C. BULLOCK MANUFACTURING COMPANY, OF SAME PLACE.

INTERCEPTING-VALVE.

SPECIFICATION forming part of Letters Patent No. 513,084, dated January 23, 1894.

Application filed June 19, 1891. Serial No. 396,852. (No model.)

To all whom it may concern:

Be it known that I, BYRON B. CARTER, of Chicago, in the county of Cook and State of Illinois, have invented certain new and useful 5 Improvements in Intercepting-Valves; and I do hereby declare that the following is a full, clear, and exact description thereof, reference being had to the accompanying drawings, and to the letters of reference marked thereon, 10 which form a part of this specification.

This invention relates to intercepting-valves for compound engines, and has for its object to automatically supply the low pressure cylinder as well as the high pressure cylinder 15 with live steam upon starting the engine, said supply to the low pressure cylinder being automatically cut off when a quantity of exhaust steam from the high pressure cylinder sufficient to supply the low pressure 20 cylinder has accumulated.

To this end my invention consists in certain novel features which will be hereinafter described and then pointed out in the appended claims.

25 In the accompanying drawings: Figure 1 is a front elevation of a compound steam engine having my improved intercepting-valve applied, only so much of the engine and its connections being shown as is necessary for a proper comprehension of the invention. Fig. 30 2 is an enlarged detail sectional view of the intercepting-valve, detached, taken on the line 2—2 of Fig. 1. Fig. 3 is a similar view of the valve casing, the valve being removed, 35 taken on the line 3—3 of Fig. 2. Fig. 4 is a detail elevation, partly in section, of a modification of the main valve.

40 Referring now more particularly to Fig. 1, A represents the high pressure cylinder of the engine, and B the low pressure cylinder, while C is the receiver, which conveys the exhaust steam from the cylinder A to the cylinder B. Live steam is supplied to the cylinder A by means of a steam supply pipe, D, from 45 the boiler. A throttle valve, d, controls the admission of steam to the cylinder A. B' represents the exhaust-pipe of the low pressure cylinder B. These parts may be of any approved form, their construction forming no 50 part of my present invention.

E represents the intercepting-valve con-

sidered as a whole. In practice, I prefer to locate this valve at the point shown, intermediate between the receiver and low pressure cylinder, and immediately adjacent to this latter, to the steam chest of which it is secured.

F represents the valve casing, which may conveniently be constructed of three parts, as shown, i. e. a lower body-portion, F', an upper body-portion, F², and a cap or cover, F³, united by flanges and bolts, as shown. In the upper portion of the valve-casing is a chamber, G, which communicates with the steam-chest of the cylinder B, while the lower portion of the 65 interior of said casing forms a chamber, G', communicating with the receiver C. Between these chambers is located a diaphragm, g, having a valve aperture, g', controlled by the main valve or intercepting-valve proper, 70 H. As shown in Fig. 2, this valve is a well known form of double-opening piston valve, comprising a disk, h, an annular upper opening or port or series of ports, h', and a ring or annulus, h², below the same, connected 75 with the disk and hub by wings, h³. Co-operating with the valve H is a cylindrical seat, I, mounted in the valve-aperture g' and having an annular port or series of ports, i, surmounted by a ring or annulus, 80 i'. With the valve in the position shown, the annulus h² closes the port i, while the annulus i' closes the port h'. Upon raising the valve both parts are opened simultaneously, and the steam passes freely through both 85 ports, obviating chattering of the valve and wire drawing of the steam.

Within the chamber G' is located a cylinder, J, into which the valve stem, K, of the valve H extends. Said valve stem is provided, 90 within said cylinder, with pistons, k and k', of different areas, the cylinder J having chambers, j and j', within which the pistons k and k' respectively fit. The cylinder J is provided at one side near its lower end 95 with a lateral port, j², between the chambers j' and G', and there is in the bottom of said cylinder a drip aperture, j³, to permit the escape of any water of condensation which may collect therein. The cylinder J is supported 100 from the lower section F' of the valve casing F by means of wings, J', connecting it there-

with, and in one of these wings, which is of a greater width than the others, there is formed an inlet passage, l , extending from the exterior of the valve to the lower portion of the chamber j , which it opens, being provided at its terminus with a downward extension, l' .

5 L represents a steam supply pipe connected at one end with the passage l , its other end being connected with the live steam supply 10 at some point intermediate between the throttle valve and high pressure cylinder, as, for instance, at the steam chest, as shown. This pipe is provided with a valve, L' , for controlling the flow of steam through the same, 15 which valve may be an ordinary steam-valve, or a reducing-valve of any approved form. From the upper portion of the chamber j , a by-pass, l^2 , formed partly in the wing J' and partly in the wall of the valve casing F , extends upward to the chamber G , into which it opens.

The valve thus organized and arranged operates in the following manner. When the throttle-valve d is closed, the several parts 25 are in the position shown in Fig. 2 of the drawings. Upon opening the throttle valve to start the engine live steam is admitted not only to the high pressure cylinder A , but also to the pipe L , and, passing through said pipe 30 and the passage l , enters the chamber j . Leaving this chamber, the live steam passes through the by-pass l^2 into the chamber G , and thence into the low pressure cylinder B , upon the piston of which it acts to cause 35 the same to aid the high pressure cylinder A in starting the engine. In its passage through the pipe L the steam passes through the valve L' , which serves, by throttling the steam, to so reduce its pressure as to prevent 40 too high a pressure in the low pressure cylinder. As an additional or alternative device for accomplishing this end, I may provide a safety-valve, M , which is shown as mounted upon the top of the valve-casing, the cover 45 F^3 of which is provided with a threaded aperture, f , to receive the same. It is obvious that any increase in pressure in the chamber G over the desired pressure, for which the safety-valve M is set, will open said valve and 50 permit the escape of a portion of the steam, reducing the pressure to the normal. The valve remains in the position shown until the pressure of the exhaust steam in the receiver from the exhaust of the high pressure cylinder A is sufficient to overcome the reduced 55 pressure of the live steam above the valve H , whereupon the said valve starts to move upward. This initial upward movement is due not only to direct pressure on the valve H , 60 but also to the pressure of the steam which enters the chamber j' through the port j^2 , and, owing to the difference in area between the pistons k and k' , aids in starting the valve H . As soon as the valve H is thus moved upward 65 the slight distance sufficient for the purpose, the live steam from the passage l , through

the medium of the downward extension l' , will enter the space in the cylinder J between the pistons k and k' , and, owing to the difference in area of said pistons, will force the valve H positively upward to the fullest extent of its movement, thereby fully opening 70 the valve, and will hold the said valve positively in this position as long as the throttle valve d is open. It will be noted that this 75 upward movement of the valve and its connected parts brings the piston k opposite the by-pass l^2 , thereby closing said by-pass and cutting off the supply of live steam to the low pressure cylinder. The exhaust steam from 80 the receiver now passes freely through the valve H to said cylinder, and the operation of the engine is normal. Upon closing the throttle valve d , the valve H returns to the position shown either by gravity or by reason 85 of a construction which I will hereinafter describe, and upon this return of the valve the steam underneath the piston k' escapes through the opening j^2 until the lower face of said piston has passed beyond said opening, 90 when the remaining steam confined between said piston and the end of the cylinder acts as a cushion to prevent violent contact of the parts as the valve closes. When the valve is about closed the steam between the pistons 95 k and k' escapes through the opening j^2 , thus relieving the valve of all lifting pressure. The parts being now in their original position, when the engine is again started the operation just described is repeated. 100

As already stated, the valve H may return to its place by gravity upon closing the throttle valve, and this especially when the arrangement is vertical, as shown. But in the case of a horizontally arranged valve, or if it be 105 deemed desirable to further insure the closing of the valve by positively actuating means, I employ the following device. Upon the valve stem K I provide a third piston, k^2 , which may take the shape of an enlargement of the 110 valve stem K , as in the construction shown, and I form upon the head, J^2 , of the cylinder J an extension, J^3 , the interior of which forms a cylindrical chamber, j^4 , within which the enlargement or piston k^2 fits. From the top 115 of this chamber a passage, n , formed partly in the extension J^3 and partly in one of the wings J' , leads to the exterior of the valve casing F , from which point a pipe, N , extends either to the steam-supply pipe D at a 120 point between the boiler and throttle valve d , or to the boiler. A constant supply of live steam to the chamber j^4 is thus obtained, whether the throttle valve be open or closed. This steam acts with sufficient force upon the 125 piston or enlargement k^2 to positively close the valve H when the steam supply is shut off at the throttle valve d , but not with sufficient force to oppose the opening of the valve H to any appreciable extent when the 130 throttle valve is open and the engine running or starting to run. Upon the opening of the

valve H after starting the engine, the steam in said chamber j^4 acts as a cushion to prevent violent contact of the parts when they reach their limit of motion. It will thus be seen that, in this structure, the valve mechanism is cushioned at the limits of its motion in both directions. By locating the port of the by-pass below the top of the chamber j , as shown, the same cushioning effect may be obtained.

It will be observed that the valve thus constructed is exceedingly simple in construction, all the working parts being inclosed in a single casing, dispensing with the cataracts and resistance cylinders heretofore employed, and having no external connections, thereby dispensing with all glands or packed joints, and obviating leakage. Moreover the main valve is opened and held open by positive steam pressure and consequently the steam from the receiver is not in the least "wire drawn" in holding the valve open, and the device is thus of superior efficiency.

So far as my present invention is concerned the form of the main valve is immaterial, and although for reasons already stated I prefer the form shown in Fig. 2, yet any approved form of unbalanced valve may be used, and I have shown, in Fig. 4, a plain disk valve, H' , which may be employed to close the valve opening g' . Moreover although for simplicity I have united several parts in one, as for instance, by employing the valve-stem to connect all the pistons with the valve, and by using the piston k as a valve for controlling the by-pass and live steam supply passage, yet I do not wish to be understood as limiting my invention to the precise construction shown, as it is capable of embodiment in other forms.

What I claim is—

1. The combination with an intercepting valve, of a cylinder having a piston connected with the intercepting valve, a passage controlled by the movement of the intercepting valve and adapted to supply steam to actuate said piston, whereby the intercepting valve will be positively opened by high pressure steam as soon as it has been partially opened by the exhaust steam, and a passage for ad-

mitting live steam to the low pressure cylinder, substantially as described.

2. The combination with an intercepting valve of a cylinder having a piston connected with the intercepting valve, passages leading from said cylinder near opposite ends thereof to the low pressure cylinder and high pressure steam supply respectively, whereby when partially lifted by the initial movement of the intercepting valve said piston will be operated by live steam pressure to completely open said valve and to close communication between said passages, substantially as described.

3. The combination with an intercepting valve, of cylinders and pistons of different areas, the latter connected with said valve, a passage controlled by the said valve for admitting live steam between the pistons to cause them to open and hold open the said valve, and a passage also controlled by said valve, for admitting live steam to the low pressure cylinder, substantially as described.

4. The combination with a valve casing having an upper and a lower chamber adapted to be connected respectively with the exhaust passage from the high pressure cylinder and the steam passage to the low pressure cylinder, of a valve aperture between said chambers, an intercepting valve controlling said aperture and having a stem provided with pistons of different areas, a cylinder inclosed in the lower chamber and having chambers fitting the pistons, a port leading from the lower chamber of the casing into the lower cylinder chamber slightly above the bottom of the latter, an inlet passage opening into the upper cylinder chamber near its lower end and leading to the upper chamber of the valve casing, the larger piston being adapted to control the ports of said inlet passage and by-pass, substantially as described.

In testimony that I claim the foregoing as my invention I affix my signature in presence of two witnesses.
